UNITED STATES PATENT OFFICE

155,072

DESIGN FOR A CHIME

Gisbert L. Bossard, Cleveland, Ohio

Application July 26, 1946, Serial No. 131,963

Term of patent 3½ years

(Cl. D72—1)

To all whom it may concern:

Be it known that I, Gisbert L. Bossard, a citizen of the United States, residing at Cleveland, in the county of Cuyahoga and State of Ohio, have invented a new, original, and ornamental Design for Chimes, of which the following is a specification, reference being had to the accompanying drawing, forming part thereof.

Fig. 1 is a perspective view of the chimes showing my new design. Fig. 2 is a top plan view thereof.

I claim:

The ornamental design for a chime, as shown.
GISBERT L. BOSSARD.
